(57) **CLAIM**

The ornamental design for a tablet stand with security mounting bracket, as shown and described.

DESCRIPTION

FIG. 1 is an isometric front view of a tablet stand with security mounting bracket showing the new design;

FIG. 2 is a front view of the design of FIG. 1;

FIG. 3 is a back side view of the design of FIG. 1;

FIG. 4 is a left side view of the design of FIG. 1;

FIG. 5 is a right top view of the design of FIG. 1;

FIG. 6 is a top view of the design of FIG. 1;

FIG. 7 is a bottom view of the design of FIG. 1;

FIG. 8 is a an isometric back view of the design of FIG. 1;

FIG. 9 is an isometric front view of a tablet stand with security mounting bracket showing a second embodiment of the new design;

FIG. 10 is a front view of the design of FIG. 9;

FIG. 11 is a back side view of the design of FIG. 9;

FIG. 12 is a left side view of the design of FIG. 9;

FIG. 13 is a right view of the design of FIG. 9;

FIG. 14 is a top view of the design of FIG. 9;

FIG. 15 is a bottom view of the design of FIG. 9; and,

FIG. 16 is a an isometric back view of the design of FIG. 9.

The broken lines showing of selected portions of the tablet stand with security mounting bracket is for environmental purposes only and forms no part of the claimed design.
